United States Patent Office

Des. 229,137
Patented Nov. 13, 1973

229,137

CHAIR

Richard M. Chapin, Charlotte, N.C., assignor to Dolly Madison Industries, Huntingburg, Ind.

Filed Apr. 20, 1972, Ser. No. 246,111

Term of patent 7 years

Int. Cl. D6—02

U.S. Cl. D6—76

FIG. 1 is a front perspective view of a chair showing my new design;

FIG. 2 is a rear perspective view thereof; and

FIG. 3 is an enlarged vertical sectional view along line 3—3 in FIG. 1.

I claim:

The ornamental design for chair, substantially as shown.
